ELECTRIC SWITCH

George J. Meuer, Milwaukee, Wis., assignor to
 Cutler-Hammer, Inc., Milwaukee, Wis., a corporation of Delaware

Application July 9, 1938, Serial No. 218,305

16 Claims. (Cl. 200—54)

This invention relates to improvements in electric switches, and more particularly to concealed door operated switches for electric refrigerators and the like.

5 A primary object of the invention is to provide an improved and simplified form of door operated switch.

Another object is to provide novel operating means for such switches.

10 Another object is to generally improve the details of construction and arrangement of the parts of such door operated switches.

Another object is to facilitate assembly of the switch parts with respect to the insulating supporting base.

15 Another object is to facilitate attachment of the circuit wires after complete assembly of the switch parts, while providing simple means for effecting concealment and protection of the wiring terminal connections.

Another object is to provide novel mounting means for the switch as a whole.

20 Another object is to provide a novel form of strain relief for the terminal connections of the circuit wires.

Another object is to provide a switch having stationary and movable contact elements of novel form.

25 Another and more specific object is to provide for concealed mounting of a switch whereby the same may be operated by the radius arm of a concealed hinge of a door.

Other objects and advantages of the invention will hereinafter appear.

30 The accompanying drawings illustrate certain embodiments of the invention which will now be described, it being understood that the invention is susceptible of embodiment in other forms without departing from the scope of the appended claims.

35 In the drawings, Figure 1 is a fragmentary view, in horizontal cross section, of a refrigerator wall and door, showing the switch in elevation and the manner in which the same is operated by the radius arm of the concealed hinge.

40 Fig. 2 is a plan view, actual size, of the switch.

Fig. 3 is an enlarged plan view similar to Fig. 2, but with the metal supporting and cover plate and the insulating plates omitted for purposes of illustration.

45 Fig. 4 is a transverse section, on the line 4—4 of Fig. 2.

Fig. 5 is a longitudinal section, on the line 5—5 of Fig. 2.

50 Fig. 6 is a fragmentary longitudinal sectional

view illustrating one of the combined contact and terminal members and the interlocking connection between the same and the insulating base of the switch.

Fig. 7 is an enlarged plan view of a modified 5 form of switch, with the metal supporting and cover plate and the insulating plates omitted for purposes of illustration.

Fig. 8 is a sectional view, on the line 8—8 of Fig. 7, with the metal supporting and cover plate 10 and the insulating plates in position.

Fig. 9 is an enlarged plan view of a further modified form of switch, with the metal supporting and cover plate and the insulating plates 15 omitted.

Fig. 10 is a sectional view, on the line 10—10 of Fig. 9, with the metal supporting and cover plate and the insulating plates in position.

Fig. 11 is a view, partly in side elevation and partly in longitudinal section, illustrating one of 20 the combined contact and terminal members and the manner in which the same is maintained in assembled relation to the insulating base of the switch, and

Fig. 12 is an end view of the switch shown in 25 Figs. 10 and 11, illustrating the simple manually operable means for releasably attaching the complete switch to a bracket or the like, shown in section.

Referring first to Figs. 1 to 6, inclusive, the 30 numeral 15 designates an insulating base adapted to be produced by a straight line molding operation. Base 15 is formed of suitable insulating material such as "Bakelite", the same being molded free from inserts of any kind. Base 15 is preferably of substantially rectangular contour (see Figs. 3 and 4), the same being of substantially greater length than width, and of substantially greater width than thickness. As best illustrated in Fig. 3, said base is provided adjacent one end 35 thereof with a transversely extending tortuous groove 16 which is adapted to accommodate the insulation-covered through wire, shown in dotted lines at 17, of a two-wire conductor or cord shown in dotted lines at 18. The other wire 19 of cord 40 18 is divided and the adjacent ends thereof are bared and hooked, as shown in dotted lines at 45 20, whereby said ends may be clamped in position by the respective binding screws 21 which take into tapped openings provided in the terminal portions 22 of a pair of combined contact and 50 terminal members of like form.

Portions 22 of said combined contact and terminal members are preferably of substantially rectangular contour, and the same are adapted 55

to seat within correspondingly shaped recesses 23 and 24, Figs. 3 and 6. As shown in Fig. 6, base 15 is further recessed to accommodate the downwardly projecting extrusions surrounding the tapped openings in portions 22, and to freely accommodate the threaded shanks of said screws, a pair of substantially cylindrical bosses 25 and 26 being formed integrally with the surface 15^a of base 15 to insure against exposure of the shanks of screws 21, and to abut one edge 27 (Fig. 1) of a metal bracket or support 28 to which the switch is attached in the manner hereinafter described.

Formed integrally with the terminal portions 22 are substantially inverted U-shaped or reflexed elements the parallel arms 22^a and 22^b of which are arranged on opposite sides of barriers 29 formed integrally with base 15, and the connecting portions 22^c of which elements are adapted to seat or rest upon the upper edges of the respective barriers 29, as shown in Figs. 3 and 6.

The adjacent vertical edges of the arms 22^b are adapted for bridging engagement by the converging sides or edges 30^a and 30^b of a contactor 30 of substantially triangular contour. The sides 30^a and 30^b of said contactor are adapted to fit closely against the correspondingly angled edges of a flat punched insulating plate or carrier 31, plate 31 having an opening 32 formed therein, and contactor 30 having an integral lug 30^c extending through said opening and bent over the inner surface of plate 31 toward the forward end of the latter, to secure said parts to each other.

Plate 31 is pivotally supported adjacent the forward end of the flat portion 33 of a metal actuating member for the switch, as by means of a rivet having a head 34 overlying a portion of one surface of said plate; a relatively large cylindrical shank portion 35 which freely penetrates a circular opening in said plate and is of slightly greater length than the thickness of plate 31; said rivet having another shank portion 36 of reduced diameter which penetrates an opening provided in said portion 33 of the actuating member and is upset over the lower surface thereof as shown at 37.

Said actuating member is provided with a second flat portion 38 (Figs. 3 and 5) offset upwardly from the portion 33 thereof, and formed integrally with portion 38 and extending upwardly at a right angle thereto is a lug 39 which is adapted to be engaged by the radius arm 40 (Fig. 1) of a concealed hinge 41 attached at one end to the refrigerator door 42, as by means of screws 43, the radius arm 40 being carried by the hinge pin 44 located within the wall 45 of the refrigerator. The upper edge 39^a of lug 39 is preferably of arcuate contour, as best illustrated in Figs. 2 and 3.

The portion 33 of the actuating member is adapted for sliding engagement with a ledge 46 (Fig. 4) in a plane below the upper surface 15^a of base 15, and the portion 38 of the actuating member is adapted for sliding engagement with a ledge 46^a in a plane only slightly below said surface 15^a, a longitudinally extending slot or recess 47 (Figs. 4 and 5) being provided to afford clearance for the upset end 37 of the rivet, and to accommodate the coiled compression spring 48. Spring 48 is provided with straight or flat end coils 48^a and 48^b, the end coil 48^a being adapted to bear against the end wall 47^a of recess 47 (Figs. 3 and 5), and the end coil 48^b being adapted to surround the lug 38^a formed integrally with and located in the plane of said portion 33 of the actuating member, said portion

33 and the connecting portion 49 between the same and portion 38 being cut away, as shown at 33^b in Figs. 3 and 5, to provide clearance for the spring.

The straight rear edge 31^a of plate 31 projects slightly beyond the root of the lug 33^a (Figs. 3 and 5), wherefore said edge is engaged by the end coil 48^b to resiliently bias said plate 31 toward its centered position, with consequent centering of contactor 30. Spring 48 is assembled as shown in Figs. 3 and 5 under a predetermined degree of compression, whereby the actuating member 33, 38 and plate 31 pivotally supported thereby are biased to a position to effect bridging engagement of contactor 30 with the adjacent edges of contact arms 22^b.

Offset downwardly from the upper surface 15^a of base 15 are ledges 15^b, 15^c (Fig. 3) located in a plane flush with the upper surfaces of the aforementioned connecting portions 22^c. Seated upon said ledges 15^b, 15^c is a flat punched insulating plate 50, the upper surface of which is flush with the upper surface 15^a of base 15. Superimposed upon surface 15^a and plate 50 is a metal plate 51 of the contour best illustrated in Fig. 2. Plate 51 is rigidly secured in position as by means of four rivets 52, the heads of which are located in countersinks or recesses provided in the lower surface of base 15, as shown in Fig. 4, and the hollow ends of which are upset over said plate, as shown in Figs. 2, 4 and 5; two of said rivets likewise penetrating registering openings in plate 50, whereby the latter is rigidly and permanently secured in position. As best illustrated in Figs. 5 and 6, plate 50 clampingly engages the connecting portions 22^c of the combined contact and terminal members to positively retain the latter in assembled relation to base 15, while providing for ready accessibility of the wiring terminal screws 21 associated therewith.

As shown in Figs. 2 and 6, the rear end of plate 51 is provided with a cut-out or notch 51^a of substantially rectangular contour to provide clearance for the aforementioned upstanding lug 39 of the actuating member. Said actuating member is normally biased by spring 48 to the position thereof shown in Figs. 2 and 5, wherein the lamp circuit or the like to be controlled by the switch is completed; and upon closure of the refrigerator door the radius arm 40 engages and moves lug 39 to the position shown in full lines in Fig. 1 and in dotted lines in Fig. 5 to interrupt the controlled circuit.

Formed integrally with plate 51 and bent downwardly at substantially right angles thereto at opposite sides of base 15 are a plurality of lugs 53, 54, 55 and 56, the free ends of which are preferably of reduced width, as shown at 53^a, 54^a, 55^a and 56^a; said free ends being bent outwardly and then inwardly, as best illustrated in Fig. 4 to provide resilient cam surfaces whereby the complete switch may be manually forced or snapped into engagement with a supporting element of suitable form.

As shown in Figs. 1 and 4 said supporting element preferably comprises a metal bracket 28 which may be an integral part of the supporting bar 57 for the hinge member 58 (Fig. 1) and pin 44. Bracket 28 is preferably provided with four circular openings, three of which are shown at 28^a, 28^b and 28^c in Figs. 1 and 4, said openings being of a size to accommodate the aforementioned bent ends 53^a, 54^a, 55^a and 56^a of the resilient lugs. As best illustrated in Fig. 4, the outer walls of the opposed pairs of openings are

so spaced as to require inward bending of the respective lugs as an incident to forcible insertion of the bent ends of the latter into said openings, the arrangement being such that when the 5 lower cam surfaces afforded by said bent ends have cleared the respective walls of said openings the upper cam surfaces (see Fig. 4) will resiliently engage the lower edges of said walls to carry base 15 into and retain the same in engagement with the exposed face of said bracket 57.

As aforesaid the sides of bosses 25 and 26 abut against the edge 27 of bracket 28 (see Figs. 1 and 4), this arrangement assisting in restraining base 15 against endwise displacement relatively to said bracket, particularly during movement of the switch parts to circuit interrupting position.

The aforementioned plate 51 is provided with a narrow integral lug 51^b located in the plane 20 thereof, the rounded free end of said lug being bent upwardly to a slight extent, as indicated at 51^c; said upwardly bent end of the lug being adapted to facilitate insertion thereunder of a flat punched insulating plate 59, of rectangular 25 contour as shown in Fig. 2. Plate 59 is adapted to seat upon ledge portions 60, 61 (Fig. 3) located in the plane of the aforementioned ledges 15^b, 15^c. Plate 59 is of the same thickness as the aforementioned plate 50 and abuts at one 30 end against the latter. The other three sides of plate 59 fit snugly within the various wall portions 15^d, 15^e, 15^f, 15^g and 15^h which are flush with the aforementioned surface 15^a of base 15. The end wall portion 15^d is preferably formed 35 as shown at 15ⁱ to provide a finger grip to facilitate removal of plate 59, as best illustrated in Fig. 5. Base 15 is provided with lateral grooves 62, 63, 64 and 65 to accommodate the aforementioned through wire 17 and the ends of wire 19 40 of cord 18. As shown in Figs. 2 and 5 plate 59 affords adequate closure or concealment of the wiring terminal connections of the switch, and said plate restrains through wire 17 against upward displacement from the tortuous passage 45 16, whereby a simple and efficient strain relief for the wiring terminal connections is provided, in the event of a pull or strain upon cord 18.

Installation of the switch in the refrigerator wall is effected in a very simple manner. Thus, 50 with the refrigerator door 42 open and prior to attachment of the usual insulating closure plate 66 (Fig. 1) to the refrigerator wall 45, the switch is wired in the manner illustrated in Fig. 3, and plate 59 is positioned as shown in Fig. 2. Thereupon the switch may be positioned upon and secured to bracket 28 by pressing upon the same, 55 with one hand, until the aforementioned resilient lugs 53^a to 56^a fully enter the respective openings in said bracket. The insulating closure plate 66 may then be attached to wall 45 to afford concealment of the hinge 41 and the switch. Spring 48 is of relatively light construction, and hence only a very slight degree of energy is required to effect opening of the 60 switch contacts as an incident to closure of door 42. Opening of the switch contacts upon closure of the door is, of course, insured. The wedging action of the contactor 30 against the adjacent edges of the stationary contacts insures 65 a good electrical connection between these parts, and the cooperative shape of these parts is such as to automatically take up any wear incident to operation of the switch.

The modified form of switch illustrated in 70 Figs. 7 and 8 is in many respects quite similar to

that shown in Figs. 1 to 6. Certain parts may be identical with corresponding parts aforescribed, and such parts have been designated by corresponding numerals of reference. The insulating base 67 in Figs. 7 and 8 is quite similar 5 to the base 15 aforescribed. The top surface of base 67 is represented by the surface portions 67^a, 67^b, 67^c and 67^d located in a common plane, said base being provided with downwardly offset ledges 68, 69 located in a common plane to accommodate insulating plate 70 (Fig. 8) in a plane 10 flush with the upper surface of said base.

Plate 70 overlies the portions 22^c connecting the arms 22^a, 22^b forming part of the combined contact and terminal members, the terminal portions of which are designated by numerals 22. Terminal portions 22, as aforescribed, are provided with tapped openings to accommodate the shanks of binding screws 21, and base 67 is provided with integral hollow bosses, one of 20 which is shown at 71 in Fig. 8, to interiorly accommodate the shanks of said screws, and exteriorly to abut one end of a supporting bracket (not shown) in a manner similar to that illustrated in Fig. 1.

The bridging contactor as shown at 72 is of cylindrical cup shape, the bottom wall 72^a thereof having a circular opening to rotatably accommodate the shank of a rivet 73, which shank likewise penetrates a registering opening in a 30 flat, punched insulating plate 74. The head of rivet 73 is located at the lower surface of plate 74 and the hollow end of said rivet is upset over said bottom wall 72^a of contactor 72 in a manner to retain said parts in assembled relation 35 while providing for rotation of contactor 72 with respect to the rivet shank. In the circuit completing position of contactor 72 the same engages at spaced points in its periphery with the adjacent vertical edges of the stationary contact arms 22^b, 22^b.

Plate 74 is slidable along the bottom wall 75 of a longitudinally extending substantially rectangular recess 76, a centrally located recess 77 opening to said bottom wall 75. Recess 77 is 40 adapted to provide clearance for the head of rivet 73 (Fig. 8) and to accommodate a portion of the cross sectional area of a coiled compression spring 78, the rear end of which abuts an end wall 77^a of a portion 77^b of recess 77, which portion 77^b is of a height slightly greater than the cross sectional area of spring 78 and opens to a ledge 79 offset downwardly from the upper surface of base 67.

Plate 74 is of the form best illustrated in 55 Fig. 7, and contactor 72 is attached thereto in a manner to project beyond the forward end thereof throughout a portion of the periphery of said contactor to insure proper engagement of the latter with a pair of stationary contacts. 60 Plate 74 is provided at its rear end with a straight edge 74^a (Fig. 7) from the mid-portion of which an integral lug 74^b projects rearwardly, as shown in Fig. 8. The forward end of spring 78 surrounds lug 74^b and abuts against said edge 65 74^a. The actuating member of the switch is provided with a flat portion 80 the forward end of which overlies, to a slight extent, the upper surface of plate 74. Plate 74 is provided with a circular opening 74^c and portion 80 is provided at its forward end with a centrally located integral lug 80^a bent downwardly at a right angle to the plane thereof and penetrating the opening 74^c in plate 74 to provide a pivotal connection 70 between said parts.

Portion 80 of the actuating member is cut away as shown at 80^b to provide a lug 80^c which overlies the aforementioned lug 74^b of plate 74, said lug 80^c being also surrounded by the forward end of spring 78. The contour of the cut away portion 80^b (Fig. 7) is such that a resilient endwise and pivoted lost motion is provided between plate 74 and the actuating member, whereby self-adjusting engagement between contactor 72 and the stationary contacts is insured. The cut away portion 80^b extends through the connecting portion 80^d to the upwardly offset flat portion 80^e of the actuating member, thus providing clearance for the spring 15 78, as best shown in Fig. 8.

The flat portion 80^e of the actuating member is slidable upon the aforementioned ledge 79, and extending upwardly at a right angle thereto is a portion 80^f to be engaged by the radius arm of 20 a concealed hinge, in the manner illustrated in Fig. 1. As aforementioned the flat punched insulating plate 70 is seated upon ledges 68 and 69 in a relation to overlie the portions 22^c of the combined contact and terminal members to 25 clamp the latter in position relatively to base 67, and to insulate the switch contacts and contactor from the metal top plate 81. Plate 81 is substantially like the plate 51 described in connection with Figs. 1 to 6. Plate 81 is secured 30 to base 67 by means of four rivets 52, two of which penetrate the insulating plate 70 to permanently retain the latter in assembled relation.

Plate 81 is likewise provided with a relatively 35 narrow forwardly projecting resilient lug 81^a which is adapted to permit forcible insertion of a flat punched insulating plate 82 (Fig. 8) in a relation to overlie and enclose the wiring terminal connections of the switch, the forward end 40 of lug 81^a being bent upwardly, as indicated at 81^b, to facilitate such insertion. Base 67 is provided with ledge portions 67^c, 67^d and 67^e upon which plate 82 is adapted to seat in a relation substantially flush with the upper surface of the 45 base, as shown in Fig. 8.

Base 67 is provided with an upwardly opening groove 67^h which is adapted to accommodate the wires shown in dotted lines at 83 and 84 in Fig. 7, base 67 being further recessed at 67ⁱ to provide 50 for leading of said wires to opposite sides of the barrier defined by ledge 67^e, and attachment of the bared ends of the wires by the respective screws 21. Groove 67^h and recess 67ⁱ (Fig. 8) are also adapted to afford a finger grip upon insulating plate 82 to facilitate removal of the latter. Plate 81 is provided at its rear end with a substantially rectangular cut away portion or notch 81^c (Fig. 8) to provide clearance for the upstanding lug 80^f of the actuating member.

Plate 81 is provided with four integral downwardly extending lugs, two of which are shown at 81^d and 81^e, and said lugs have bent ends, as shown at 81^f and 81^g to provide a snap fastening or connection between the same and a bracket member having suitable openings, in the manner illustrated in Fig. 1, the bosses, one of which is shown at 71 in Fig. 8, assisting in retaining the complete switch in proper relation to the aforementioned supporting bracket.

The switch illustrated in Figs. 9 to 12, inclusive, is quite similar in structure to each of the switches aforescribed. The switch now to be described differs from the switches aforescribed primarily in respect of the form of the combined contact and wiring terminal members, and in re-

spect of the means for attaching the switch as a whole to a suitable supporting bracket.

The molded insulating base 85 is shown as provided with a tortuous through-wire passage or groove 86, and laterally extending grooves 87 and 88 which communicate with recesses 89 and 90 adapted to receive a pair of combined contact and wiring terminal members the terminal portions 91 of which are respectively provided with tapped openings for cooperation with the shanks of binding screws 21. Base 85 is provided with a pair of downwardly projecting hollow bosses 92 and 93, which are interiorly adapted to accommodate the shanks of said binding screws and exteriorly adapted to abut an edge portion of a supporting 15 bracket 94 (Fig. 12) of suitable form.

Each terminal portion 91 is provided with a portion 91^a of reduced width, the walls of recesses 89 and 90 being shaped to accommodate portions 91 and 91^a with a fairly close fit, and to likewise accommodate with a fairly close fit the contact portions 91^b formed integrally with portions 91 and bent upwardly at substantially a right angle thereto (Figs. 9 and 11). Base 85 is provided with a substantially rectangular recess 95 extending from the front face of the contact portions 91^b to the wall shown in dotted lines at 95^a in Fig. 9 and in full lines in Fig. 10, the bottom wall of said recess being designated by the numeral 95^b, and said bottom wall having an extension 95^c at the forward end thereof to provide for engagement of the angled sides 96^a, 96^b of contactor 96 with the adjacent vertical edges of contact portions 91^b.

Contactor 96 is formed of sheet metal, the same 35 being attached by a plurality of integral lugs 96^c, 96^d and 96^e to a flat punched insulating plate 97 of the form best illustrated in full and dotted lines in Fig. 9. Lug 96^c penetrates an opening 97^a provided in plate 97, and lugs 96^d and 96^e 40 are formed integrally with the aforementioned angled sides 96^b and 96^a of the contactor, all of said lugs being bent inwardly over the lower surface of plate 97 as shown in dotted lines in Fig. 9. Plate 97 is provided with a second opening 97^b 45 which accommodates a downwardly extending lug 80^a formed integrally with the flat portion 80 of an actuating member (which may be identical with that shown in Figs. 7 and 8, with portions thereof bearing like numerals of reference), 50 to provide a pivotal connection between plate 97 and the actuating member.

Plate 97 is provided with an integral lug 97^c (Fig. 10) which underlies and is substantially aligned with lug 80^c formed on portion 80 of the 55 actuating member, said lugs being jointly surrounded by the forward end coils of a spring 78, in the manner described in connection with Figs. 7 and 8. Plate 97 is adapted for sliding movement upon the bottom wall 95^b of recess 95, and the portion 80^e of the actuating member is slid- 60 able upon the ledge 98 offset downwardly from the upper surface of base 85. Spring 78 acts in the manner aforescribed to effect centering of insulating plate 97 while permitting the desired 65 degree of self-adjustment of the latter and of the contactor 96 when moved into engagement with the stationary contact portions 91^b, said spring acting to bias said contactor into bridging engagement with said contact portions upon opening 70 of the refrigerator door, as aforescribed.

A flat punched insulating plate 99 (Figs. 10 and 11) is seated upon the ledges 100 and 101 (Fig. 9) and is adapted for clamping engagement with the upper edges of the respective contact por- 75

tions 91^b to retain the combined contact and terminal members in assembled relation to the base. A metal plate 102 is superimposed upon the upper surface of base 85 and overlies the major portion of plate 99, said plate 102 being secured to said base as by means of four rivets 52, two of which penetrate plate 99 to rigidly and permanently secure the latter in position. As shown in Fig. 10, plate 102 overlies the portion 80^c of the actuating member in a relation to permit and assist in guiding the sliding movement of the latter. Plate 102 is notched or cut away at 102^a (Figs. 10 and 12) to provide clearance for the upstanding portion 80^c of the actuating member, and said plate is provided with a relatively narrow integral lug 102^b, lug 102^b being flexible or resilient to permit forcible insertion or removal of a flat punched insulating plate 103 which overlies the wire passage 86 and the terminal screws 21. Lug 102^b is bent upwardly at 102^c to facilitate insertion of plate 103, and base 85 is formed as shown at 104 (Figs. 9 and 10) to facilitate manual removal of said plate.

Formed integrally with plate 102 at one side edge thereof, and bent downwardly at substantially a right angle thereto are a pair of lugs 102^d and 102^e, the lower ends of which are bent outwardly at a right angle thereto, as shown in dotted lines at 102^f, 102^g in Figs. 10 and 11 and 30 in full lines in Fig. 12. Extending downwardly from the opposite side edge of plate 102 is a lug 102^h having a reduced portion 102ⁱ the lower end 102^j of which extends outwardly and downwardly at an angle of substantially more than 90 degrees. 35 The supporting bracket 94 (Fig. 12) is provided with a pair of openings such as 94^a into which the lugs 102^d, 102^e may be inserted to effect hooked engagement of the bent ends 102^f, 102^g thereof with the inner surface of bracket 94. 40 The other lug 102^h is manually pressed inwardly to the dotted line position thereof shown in Fig. 12 to provide clearance for the bent end 102^j of portion 102ⁱ with respect to an opening 94^b in bracket 94, and upon manual release of lug 102^h 45 said end 102^j moves to the full line position thereof shown in Fig. 12 to releasably retain the switch in proper relation to bracket 94. Lug 80^c of the switch actuating member is adapted to be engaged by the radius arm of a concealed hinge, as heretofore described. As shown in Fig. 9, base 50 85 is provided with ledge portions 105 located in a common plane upon which the insulating plate 103 is adapted to seat in a relation substantially flush with the upper surface of said base (Figs. 55 10 and 11).

It will be understood that by slight modification of the base 15 shown in Figs. 1 to 6 and of base 67 in Figs. 7 and 8, combined contact and terminal members of the character shown in Figs. 60 9 to 12 might be employed. Various other possible changes in the details of construction and arrangement of the switch parts will be apparent to those skilled in the art from the foregoing description.

65 What I claim as new and desire to secure by Letters Patent is:

1. In a door operated switch adapted for concealed mounting, in combination, a molded insulating base comprising a single substantially 70 rectangular block having a recess formed in one surface thereof, a substantially flat sheet metal cover member secured to said base and overlying said recess, an actuating member having a portion interposed between said metal cover member 75 and said base and slidable in a plane parallel

thereto, said actuating member having a substantially right angled lug extending beyond said metal cover member for engagement by an operating element of suitable form, a pair of spaced stationary contacts located within said recess, a contactor movable rectilinearly solely within said recess into and out of bridging engagement with said stationary contacts, said contactor being pivoted to and insulated from said actuating member to provide for positive movement of the 10 former with the latter in each direction, and a coiled spring engaged under compression at one end with said insulating base and at the other end with said actuating member and said contactor to bias the same jointly to only one extreme position thereof relatively to said base, said lug when engaged by said operating member providing for movement of said actuating member and said contactor against the bias of said spring. 15

2. In a door operated switch, in combination, a 20 molded insulating base having a recess formed in the upper surface thereof, a cover member comprising a flat plate secured to the upper surface of said base and overlying said recess, an actuating member having a portion interposed 25 between said cover member and said base in a plane substantially flush with the upper surface of the latter and slidable with respect thereto, said actuating member having a lug extending therefrom at substantially a right angle thereto 30 beyond the outer surface of said cover member for engagement by an operating element of suitable form, a pair of spaced sheet metal stationary contacts located within said recess, a stamped sheet metal contactor movable into and out of bridging engagement with said stationary contacts, means including a pivoted pin providing a positive driving connection between said actuating member and said contactor, a coiled compression spring engaged at one end with said base 35 and at its other end with said actuating member and said contactor to bias the same jointly to only one extreme position thereof with respect to said base, said last mentioned end of the spring being so engaged with said actuating member 40 and said contactor on opposite sides of said pivotal connection as to normally hold said contactor in a substantially centered relation to said actuating member, and said last mentioned end of the spring yielding to permit relative lateral movement of said contactor with respect to said actuating member as an incident to engagement of said contactor with said stationary contacts. 45

3. In a door operated switch, in combination, a 50 recessed molded insulating base, a pair of spaced stationary contacts and a contactor located within the recess in said base, an insulating carrier for said contactor, an actuating member having a driving connection with said carrier, said 55 driving connection providing for movement of said carrier relatively to said actuating member whereby said contactor is self-adjustable with respect to said contacts, a coiled compression spring interposed between an end wall of said 60 recess and said carrier to bias said actuating member and said contactor to a given extreme position wherein the latter engages said stationary contacts, said spring tending to maintain said carrier in centered relation to said actuating member, said actuating member having cut away 65 and offset portions adapted to provide clearance for said spring, said actuating member having a lug extending at substantially a right angle to the offset portion thereof for engagement by an op- 70

- erating element of suitable form, a metal cover plate secured to said base, an insulating member interposed between said cover plate and said base and adapted to overlie said contactor in all positions of the latter, said stationary contacts being seated upon said base, and said insulating member overlying portions of said contacts to rigidly and permanently secure the latter in position.
4. In a door operated switch, in combination, a recessed molded insulating base, a pair of spaced stationary contacts and a contactor located within the recess in said base, an insulating carrier for said contactor, an actuating member having a driving connection with said carrier, said driving connection providing for movement of said carrier relatively to said actuating member whereby said contactor is self-adjustable with respect to said contacts, a coiled compression spring interposed between an end wall of said recess and said carrier to bias said actuating member and said contactor to a given extreme position wherein the latter engages said stationary contacts, said spring tending to maintain said carrier in centered relation to said actuating member, said actuating member having cut away and offset portions adapted to provide clearance for said spring, said actuating member having a lug extending at substantially a right angle to the offset portion thereof for engagement by an operating element of suitable form, a metal cover plate secured to said base, an insulating member interposed between said cover plate and said base and adapted to overlie said contactor in all positions of the latter, said stationary contacts being seated upon said base, said insulating member overlying portions of said contacts to rigidly and permanently secure the latter in position, said cover plate having a plurality of resilient lugs extending at substantially right angles thereto in parallel relation to and beyond opposite sides respectively of said base, said lugs having bent end portions, a metal plate having openings formed therein, said lugs being bendable to provide for passage of the bent ends thereof through or withdrawal thereof from said plate openings, and said bent ends resiliently cooperating with the inner surface of said metal plate to releasably retain said switch in proper position.
5. In a door operated electric switch, in combination, a substantially rectangular molded insulating base of substantially greater length than width and of substantially greater width than thickness, said base having a recess formed in one surface thereof, a plurality of contacts located within said recess, one of said contacts being movable rectilinearly in a plane parallel to said surface of said base into and out of bridging engagement with other of said contacts, a stamped sheet metal actuating member having a portion thereof located within said recess and slidably movable in a plane parallel to said surface of the base and another portion projecting upwardly from said recess at substantially a right angle to said first mentioned portion of said actuating member, means providing a positive driving connection between said actuating member and said movable contact to insure movement of the latter simultaneously with the former in each direction, a coiled compression spring engaged at one end with said base and acting at its other end to bias said actuating member and said movable contact jointly to only one extreme position thereof relatively to said base, a flat sheet metal cover member attached to said base and overlying at least a portion of said recess, said metal cover member cooperating with said base to assist in guiding said actuating member, and a flat, punched insulating plate interposed between said metal cover member and said contacts in the engaged and disengaged positions of the latter.
6. In a door operated electric switch, in combination, a substantially rectangular molded insulating base of substantially greater length than width and of substantially greater width than thickness, said base having a recess formed in one surface thereof, a plurality of contacts located within said recess, one of said contacts being movable longitudinally of said base into and out of bridging engagement with other of said contacts, an actuating member having a portion thereof located within said recess and another portion projecting from said recess at substantially a right angle to said base, means providing a driving connection between said actuating member and said movable contact, a coiled compression spring acting to bias said actuating member and said movable contact jointly to a given extreme position thereof, a metal cover member attached to said base and overlying at least a portion of said recess, said cover member cooperating with said base to assist in guiding said actuating member, an insulating plate interposed between said cover member and said contacts in the engaged and disengaged positions of the latter, said cover member having a plurality of resilient lugs formed integrally therewith and extending rearwardly therefrom in spaced relation to the respective sides of said base beyond the rear surface of the latter, said lugs having outward bends adjacent to the free ends thereof, a metal bracket having openings formed therein in substantial alignment with said lugs, the free ends of said lugs being insertable into said openings, and the bends in said lugs being resiliently engageable with the inner edges of said openings to releasably retain said switch in assembled relation to said bracket.
7. In a door operated switch, in combination, a molded insulating base having a recess formed in one surface thereof, a pair of one-piece combined contact and wiring terminal members loosely positioned in spaced relation within said recess and restrained by the walls thereof against relative movement in the plane of said base, the contact portions of said members having adjacent vertical edges, a contactor slidably movable into and out of bridging engagement with said edges, an insulating carrier for said contactor, an actuating member having a pivotal driving connection with said carrier, a coiled compression spring interposed between an end wall of said recess and said carrier and actuating member whereby the latter and said contactor are biased to a given extreme position, said spring also acting to resiliently retain said carrier in a given relation to said actuating member, said actuating member comprising a punched and stamped metal piece having cut away and offset portions to jointly provide clearance for said spring, said base having a ledge upon which said offset portion is adapted to slide in a plane slightly below the first mentioned surface of said base, a metal cover plate rigidly secured to said base and overlying a portion of said recess, said cover plate overlying at least a part of the offset portion of said actuating member to assist in guiding the latter, said offset portion having an integral lug extending

therefrom at substantially a right angle thereto for engagement by a movable operating element of suitable form, and said plate being formed to provide clearance for said lug.

5 8. In a door operated switch, in combination, a molded insulating base having a recess formed in one surface thereof, a pair of one-piece combined contact and wiring terminal members loosely positioned in spaced relation within said recess and restrained by the walls thereof against relative movement in the plane of said base, the contact portions of said members having adjacent vertical edges, a contactor slidably movable into and out of bridging engagement with said edges, 10 an insulating carrier for said contactor, an actuating member having a pivotal driving connection with said carrier, a coiled compression spring interposed between an end wall of said recess and said carrier and actuating member whereby the latter and said contactor are biased to a given extreme position, said spring also acting to resiliently retain said carrier in a given relation to said actuating member, said actuating member comprising a punched and stamped metal piece 15 having cut away and offset portions to jointly provide clearance for said spring, said base having a ledge upon which said offset portion is adapted to slide in a plane slightly below the first mentioned surface of said base, a metal cover plate rigidly secured to said base and overlying a portion of said recess, said cover plate overlying at least a part of the offset portion of said actuating member to assist in guiding the latter, said offset portion having an integral lug extending 20 therefrom at substantially a right angle thereto for engagement by a movable operating element of suitable form, said plate being formed to provide clearance for said lug, and an insulating plate interposed between said cover member and said base and overlying the contact portions of said combined contact and wiring terminal members to rigidly and permanently secure the same against upward displacement from said recess.

45 9. In a door operated switch, in combination, a molded insulating base having a recess formed in one surface thereof, a pair of one-piece combined contact and wiring terminal members loosely positioned in spaced relation within said recess and restrained by the walls thereof against relative movement in the plane of said base, the contact portions of said members having adjacent vertical edges, a contactor slidably movable into and out of bridging engagement with said edges, 50 an insulating carrier for said contactor, an actuating member having a pivotal driving connection with said carrier, a coiled compression spring interposed between an end wall of said recess and said carrier and actuating member whereby the latter and said contactor are biased to a given extreme position, said spring also acting to resiliently retain said carrier in a given relation to said actuating member, said actuating member comprising a punched and stamped metal piece 55 having cut away and offset portions to jointly provide clearance for said spring, said base having a ledge upon which said offset portion is adapted to slide in a plane slightly below the first mentioned surface of said base, a metal cover plate rigidly secured to said base and overlying a portion of said recess, said cover plate overlying at least a part of the offset portion of said actuating member to assist in guiding the latter, said offset portion having an integral lug 60 extending therefrom at substantially a right angle thereto for engagement by a movable operating element of suitable form, said plate being formed to provide clearance for said lug, an insulating plate interposed between said cover member and said base and overlying the contact portions of said combined contact and wiring terminal members to rigidly and permanently secure the same against upward displacement from said recess, said cover member having a relatively narrow resilient lug extending over that portion of the base recess in which the terminal portions of the combined contact and terminal members are located, said base having other ledge portions formed thereon, a flat insulating plate insertable under said last mentioned lug 65 and releasably retained thereby in seated relation to said ledge portions, said last mentioned lug having an upwardly bent end to facilitate insertion of said insulating plate, and said base being recessed to provide for manual gripping of said 70 plate, whereby removal of the latter is facilitated.

75 11. In a device of the character described, in combination, a wall and a door having a concealed hinge connection therebetween, said hinge connection including a radius arm positioned 75

extending therefrom at substantially a right angle thereto for engagement by a movable operating element of suitable form, said plate being formed to provide clearance for said lug, an insulating plate interposed between said cover member and said base and overlying the contact portions of said combined contact and wiring terminal members to rigidly and permanently secure the same against upward displacement from said recess, said cover member having a relatively narrow resilient lug extending over that portion of the base recess in which the terminal portions of the combined contact and terminal members are located, said base having other ledge portions formed thereon, and a flat insulating plate insertable under said last mentioned lug and releasably retained thereby in seated relation to said ledge portions.

10 12. In a door operated switch, in combination, a molded insulating base having a recess formed in one surface thereof, a pair of one-piece combined contact and wiring terminal members loosely positioned in spaced relation within said recess and restrained by the walls thereof against relative movement in the plane of said base, the contact portions of said members having adjacent vertical edges, a contactor slidably movable into and out of bridging engagement with said edges, 15 an insulating carrier for said contactor, an actuating member having a pivotal driving connection with said carrier, a coiled compression spring interposed between an end wall of said recess and said carrier and actuating member whereby the latter and said contactor are biased to a given extreme position, said spring also acting to resiliently retain said carrier in a given relation to said actuating member, said actuating member comprising a punched and stamped metal piece 20 having cut away and offset portions to jointly provide clearance for said spring, said base having a ledge upon which said offset portion is adapted to slide in a plane slightly below the first mentioned surface of said base, a metal cover plate rigidly secured to said base and overlying a portion of said recess, said cover plate overlying at least a part of the offset portion of said actuating member to assist in guiding the latter, said offset portion having an integral lug 25 extending therefrom at substantially a right angle thereto for engagement by a movable operating element of suitable form, said plate being formed to provide clearance for said lug, an insulating plate interposed between said cover member and said base and overlying the contact portions of said combined contact and wiring terminal members to rigidly and permanently secure the same against upward displacement from said recess, said cover member having a relatively narrow resilient lug extending over that portion of the base recess in which the terminal portions of the combined contact and terminal members are located, said base having other ledge portions formed thereon, a flat insulating plate insertable under said last mentioned lug 30 and releasably retained thereby in seated relation to said ledge portions, said last mentioned lug having an upwardly bent end to facilitate insertion of said insulating plate, and said base being recessed to provide for manual gripping of said 35 plate, whereby removal of the latter is facilitated.

13. In a device of the character described, in combination, a wall and a door having a concealed hinge connection therebetween, said hinge connection including a radius arm positioned 40

- within said wall, a switch mechanism supported within said wall, said switch mechanism including an actuating member spring biased to a given extreme position, said actuating member including a lug extending therefrom in the path of said radius arm for operation by the latter against said bias upon movement of said door toward closed position relatively to said wall, said switch mechanism including a recessed molded insulating base, a metal cover plate overlying the recess in said base, said cover plate having a plurality of resilient lugs extending rearwardly therefrom beyond said base, a metal bracket within said wall, said bracket having openings formed therein in substantial alinement with said lugs, and said lugs having bent end portions engageable under tension with the walls of said openings to releasably retain said switch mechanism in assembled relation to said bracket.
12. In a device of the character described, in combination a wall and a door, said wall having a recess formed therein and said door having a hinge member including an arcuate portion rigidly attached thereto and a radius arm portion pivotally supported within said recess, a cover member for said recess having an opening to provide clearance for said arcuate portion while providing for concealment of said radius arm in all positions of said door, a flat metal bracket arranged in spaced relation to the free end of said radius arm, said bracket having a plurality of spaced openings formed therein, a switch mechanism including a molded insulating base having a rear surface adapted to seat flatwise against said bracket, said base having a recess opening to the forward surface thereof, a metal cover member overlying at least a portion of said recess, said cover member having a plurality of resilient lugs extending rearwardly therefrom and adapted to penetrate said bracket openings, the free ends of said lugs being deformed to provide for resilient and releasable retention of said base in assembled relation to said bracket, an actuating member slidably interposed between said cover member and said base, a coiled compression spring located within said recess and engaged with said actuating member to bias the latter to a given extreme position, and said actuating member having an integral lug extending at substantially a right angle to said cover plate and located in the path of said radius arm for operation by the latter against the bias of said spring upon movement of said door toward closed position.
13. In a device of the character described, in combination, a wall and a door, said wall having a recess formed therein and said door having a hinge member including an arcuate portion rigidly attached thereto and a radius arm portion pivotally supported within said recess, a cover member for said recess having an opening to provide clearance for said arcuate portion while providing for concealment of said radius arm in all positions of said door, a flat metal bracket arranged in spaced relation to the free end of said radius arm, said bracket having a plurality of spaced openings formed therein, a switch mechanism including a molded insulating base having a rear surface adapted to seat flatwise against said bracket, said base having a recess opening to the forward surface thereof, a metal cover member overlying at least a portion of said recess, said cover member having a plurality of resilient lugs extending rearwardly therefrom and
- adapted to penetrate said bracket openings, the free ends of said lugs being deformed to provide for resilient and releasable retention of said base in assembled relation to said bracket, an actuating member slidably interposed between said cover member and said base, a coiled compression spring located within said recess and engaged with said actuating member to bias the latter to a given extreme position, said actuating member having an integral lug extending at substantially a right angle to said cover plate and located in the path of said radius arm for operation by the latter against the bias of said spring upon movement of said door toward closed position, a pair of spaced stationary contacts located within said recess, a contactor slideable within said recess into and out of bridging engagement with said contacts, and means providing both a positive driving connection and a resilient lost motion connection between said actuating member and said contactor.
14. In an electric switch, in combination, a molded insulating base recessed from one surface thereof to accommodate a pair of wiring terminal plates positioned flatwise in a common plane in side by side relationship with an insulating barrier therebetween, stationary switch contacts formed integrally with the respective terminal plates and having contact edge portions laterally aligned with but spaced from each other, said base having a pair of laterally extending aligned notches formed in said surface thereof and leading to said terminal plates to accommodate a divided circuit wire the bare ends of which are attached to said terminal plates, said base having a second pair of laterally extending aligned notches which communicate with a zigzag groove formed therebetween, said groove being adapted to accommodate an insulated through wire bent to conform thereto, a flat, punched plate of insulating material overlying said terminal plates and said groove to retain said through wire within the latter, said through wire forming part of a two-wire cord whereby the former serves as a strain relief for the wire ends attached to said terminal plates, a punched and stamped sheet metal plate the main body portion of which is rigidly and permanently secured to said surface of the base, said metal plate having a resilient lug at one end of said main body portion thereof overlying said insulating plate to releasably retain the latter in assembled position, a second flat, punched plate of insulating material interposed between the main body portion of said metal plate and said base and engaged with said contacts to retain the latter in assembled position, and a contactor movable rectilinearly relatively to said base into and out of bridging engagement with the edge portions of said contacts.
15. In a device of the character described, in combination, a wall and a door having a concealed hinge connection therebetween, said hinge connection comprising an arcuate portion rigidly attached to said door and a radius arm positioned within said wall and pivotally attached to the latter, a switch mechanism supported within said wall, said switch mechanism including an actuating member spring biased to a given extreme position to normally provide for closure of the cooperating contacts of the switch mechanism, said actuating member including an element extending therefrom in the path of said radius arm for operation by the latter against said bias upon movement of said door toward closed position.

5 relatively to said wall, the supporting means for said switch comprising a metal cover member having at least one resilient lug formed integrally therewith and extending therefrom at substantially a right angle thereto, said lug having a bend adjacent the free end thereof, and said wall having an opening formed in a part thereof to accommodate the bent end of said resilient lug and to provide a snap interlocking connection with

10 the latter.

16. In a door operated switch adapted for concealed mounting, in combination, a single insulating base, a substantially flat sheet metal cover member secured to and overlying said base, 15 an actuating member having a portion interposed between said metal cover member and said base and slideable in a plane parallel thereto, said ac-

tuating member having an element extending therefrom at substantially a right angle thereto beyond the outer surface of said cover member for engagement by an operating element of suitable form, a pair of spaced stationary contacts 5 carried by said base, a contactor movable rectilinearly into and out of bridging engagement with said stationary contacts, means providing a positive, insulating driving connection between said actuating member and said contactor, and a 10 coiled spring engaged under compression at one end with said insulating base and at the other end with said actuating member and said contactor to continuously bias the same jointly toward only one extreme position thereof relatively to said base. 15

GEORGE J. MEUER.
